BUILDING UNIT

Filed Sept. 15, 1930

Henry R. Reeder &
William Scott

BY *Victor J. Evans*

UNITED STATES PATENT OFFICE

HENRY R. REEDER AND WILLIAM SCOTT, OF CHICAGO, ILLINOIS

BUILDING UNIT

Application filed September 15, 1930. Serial No. 482,065.

This invention relates to certain novel improvements in building units, and has for its principal object the provision of an improved construction of this character which will be highly efficient in use and economical in manufacture.

The salient object of this invention is the provision of an improved unit for building construction embodying dead air chambers which provide an improved insulation against heat and cold.

Another object of the invention is the provision of an improved unit for building construction which may be quickly and economically assembled with a minimum of labor.

A further object of the invention is the provision of an improved building unit providing a substitute for brick and the like which provides a surface to which plaster or the like may be applied directly without the use of laths or the like.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is a top plan view of a typical building wall section showing a preferred form of construction for our invention and depicting the invention in assembled position;

Fig. 2 is a sectional view taken substantially on the line 2-2 in Fig. 1;

Fig. 3 is a sectional view taken substantially on the line 3-3 in Fig. 1;

Fig. 4 is a perspective view of one unit of the invention showing a preferred construction of the plaster receiving surface;

Fig. 5 is a top plan view depicting a modified form of construction; and

Fig. 6 is a fragmentary side elevational view taken substantially on the line 6-6 in Fig. 1, showing one form of ornamentation applied to the outer surface of the unit.

Referring to the drawing wherein the preferred embodiments of our invention are illustrated, generically indicated at 10 is the body portion of one section of our improved build-

ing unit which is preferably formed of any suitable refractory material such as is employed in the manufacture of brick, tile and the like. As shown in Figs. 1 to 4 inclusive, the section 10 comprises oppositely extending side wall portions 11 and 12 and end portions 13 and 14 which define the walls of a dead air chamber 15. Provided in the end portion 13 of the section 10 is a tongue 16 and provided in the opposite end portion 14 is a recess 17. By referring to Fig. 1 it may be seen that the tongue 16 is narrower than the recess 17 so that in assembling the invention the tongue 16 of one section 10 is inserted into the recess 17 of the next adjacent unit and space is provided for the insertion of a suitable binding agent such as mortar 18 or the like therebetween.

In the form of construction of our invention depicted in Figs. 1 to 4 each building unit comprises the section 10 and a substantially similar section 19 which is joined to the section 10 by means of straps 20 which include offset portions 21. The straps 20 may be made of any suitable material such, for example, as steel and these straps are rigidly and permanently secured in position in the sections 10 and 19 during the manufacture thereof. While two straps 20 are depicted between each pair of sections 10 and 19 it is manifest that this number may be varied without departing from the purview of our invention.

The section 19 comprises side wall portions 22 and 23 and end portions 24 and 25 which define a dead air chamber 26, which is preferably somewhat wider than the air chamber 15. Provided in each section 19 is a tongue portion 27, similar to the tongue portion 16, and a recess 28 similar to the recess 17. By referring to Fig. 1 it may be seen that in assembling our improved unit the tongue 27 of one section 19 is inserted in the groove 28 of the next adjacent section 19 and secured in position by means of mortar 18 or the like.

As shown in Fig. 2 there is provided in each of the straps 20 a plurality of openings 29 and in the manufacture of our improved building unit it may be seen that the refrac-

tory material of which the unit is made is interspersed through these openings 29 thereby exerting a binding action to secure the straps 20 in position. It is manifest, therefore, that the straps 20 secure the section 10 and the section 19 of each unit together while these straps 20 likewise act as reenforcement and due to the offset portions 21 lateral movement of the two sections in each unit, with respect to each other, is prevented. As shown in Fig. 1, the offset portions 21 of the straps 20 are preferably substantially U-shaped and have the bight portions thereof directed inwardly with a portion of the bight portion of each strap extended across an air chamber 30 which is formed between the sections 10 and 19 when our improved unit is assembled in a wall such as shown in Fig. 1.

Provided in the outer surface of the wall 20 of the section 19 is a net work of intersecting grooves comprising vertically extending grooves 31 and longitudinally extending grooves 32 which provide a retaining surface for plaster or the like.

In Fig. 5 a modified form of construction is depicted and in this instance the sections 10 and 19 have provided therebetween a middle section 33, thereby defining air chambers 34 and 35. In this form of construction straps 36 are provided which are substantially similar to the straps 20 but include longer offset portions 37 which project through the section 33.

Depicted in Fig. 6 is one form of ornamental surface that may be formed in the surface of the outer wall 11 of the section 10 though it is understood that any desired form of ornamental surfacing may be formed on the surface of the outer wall.

From the foregoing description of our invention it is manifest that we have provided an improved building unit which embodies dead air chambers providing a highly efficient wall insulation against heat and cold. It is likewise apparent that while being durable, economical and simple in construction our improved unit permits of rapid assembly in building thereby effecting a material economy in labor.

While we have illustrated and described the preferred form of construction for carrying our invention into effect, this is capable of variation and modification, without departing from the spirit of the invention. We, therefore, do not wish to be limited to the precise details of construction set forth, but desire to avail ourselves of such variations and modifications as come within the scope of the appended claims.

Having thus described our invention what we claim as new and desire to protect by Letters Patent is:

1. A building unit comprising spaced apart sections defining an air chamber therebe-

tween, each of said sections having an air chamber defined interiorly thereof, a tongue in one end portion of each of said sections, each of said sections having a groove formed therein in the end portion thereof opposite said tongue, the tongue of one section being adapted in assembled position to be fitted into the groove of the next adjacent corresponding section, and means for securing said sections together in spaced apart relation to define said first-named air chamber therebetween, said means including strap members embedded in said sections and each of said strap members including an offset portion extended across said first-named air chamber and having its ends embedded in said sections, and the portions of said strap members at opposite sides of said offset portions having perforations therein through which the material composing the said sections is adapted to extend.

2. A building unit comprising spaced apart outer sections, a middle section disposed between and spaced apart from said outer sections defining a plurality of air chambers therebetween, each of said outer sections having an air chamber defined interiorly thereof, said outer sections including end portions, a tongue in one end portion of each of said outer sections, each of said outer sections having a groove formed therein in the end portion thereof opposite said tongue, the tongue of one outer section being adapted in assembled position to be fitted into the groove of the next adjacent corresponding section, and means for securing said outer sections and said middle section in spaced relation to define said first-named air chambers, said means including strap members provided with offset portions extended across said first-named air chambers and through said middle section.

3. A building unit comprising spaced apart outer sections each having an intrawall air chamber defined therein, a middle section disposed between and spaced from said outer sections to provide therewith a plurality of interwall air chambers, and strap members each including an offset portion extended through said middle section and interwall chambers, and the ends of said offset portions and the remaining portions of said strap members being embedded in said outer sections at opposite ends of said intrawall air chambers.

4. A building unit comprising spaced sections each having an intrawall air chamber defined therein and providing therebetween an interwall air chamber, and means for connecting said sections together in spaced relationship to provide said interwall chamber, said means comprising a member including an offset portion extended across said interwall chamber and having its ends embedded in said sections at the ends of said

intrawall chambers, the embedded portions of said member having apertures therein through which the material composing said sections is bonded.

5 In testimony whereof we affix our signatures.

HENRY R. REEDER.
WILLIAM SCOTT.
